UNITED STATES PATENT OFFICE.

GEORGE H. WILSON, OF LOUISVILLE, KENTUCKY.

TOBACCO PIPE.

Application filed February 12, 1925. Serial No. 8,781.

This invention relates to tobacco pipes and has for one of its objects an improved construction in which provision is made for inducing perfect and even combustion of the tobacco.

Another object of the invention is to provide means in a tobacco pipe to prevent chocking of the stem channel when the tobacco is compressed in the act of filling the bowl.

A further object of the invention is the construction of a tobacco pipe having means for cooling the smoke.

Still another object of the invention is to provide a tobacco pipe in which the above features are combined to produce a superior smoking appliance both with respect to the healthful and agreeable qualities of the smoke and the unobjectionable character of the combustion products diffused into the atmosphere.

Other objects will appear as the following description of a preferred embodiment of the invention develops.

In the drawings:

Figure 1 represents a side elevation of a tobacco pipe embracing my invention, a part thereof being shown in section.

Figure 2 is a section taken along the line $a-a$ of Figure 1, and viewed in the direction of the upper arrow.

Figure 3 is a similar section viewed in the direction of the lower arrow.

Figure 4 is a section taken along the line $4-4$ of Figure 1.

Referring now in detail to the several figures, the numeral 1 represents in general the pipe, which consists of the bowl portion 2 and the stem 3. The stem, in the present instance is shown as being detachable from the bowl portion and fitting into a bore 4 therein with a frictional engagement. The bowl portion is provided with a combustion chamber 5 which may be of any desired form but is here illustrated as being cylindrical. Near the base of the combustion chamber and on that side which faces the stem, the bowl portion is undercut forming a suction or mixing chamber 6, the upper wall 7 of which overhangs said mixing chamber. A stem channel 9 communicates with said mixing chamber and with the bore in the stem of the pipe. An annular groove

8 is formed in the bowl portion circumferentially of the combustion chamber and near the base thereof, said groove merging into the upper part of the mixing chamber.

Tobacco, being non-fluid, will not transmit pressure equally in all directions, therefore when tobacco is compressed into the combustion chamber in the act of filling the pipe it will not become equally compressed into the mixing chamber 6 or the annular groove 8. Stray flakes of tobacco may find their way into both of these spaces, but in the main the emptiness of said spaces is preserved so that the suction through the stem channel 9 remains unimpaired by too close packing of the tobacco. Ample air for complete combustion is therefore assured and the smoke is drawn without appreciable effort through the stem. Perfect and even combustion is also obtained by reason of the fact that the annular groove 8 is open circumferentially at all points to the tobacco so that the suction is uniform throughout the mass of tobacco in the combustion chamber. This is a condition under which the formation of distillates, such as nicotine and creosote, will not take place.

It is preferable, in order to obtain a cool smoke, to provide the bowl portion with an air bleed passage 10. This passage preferably communicates at one end with the atmosphere and at the other with the mixing chamber 6. In account of the relatively smaller cross sectional area of the bleed passage 10 to the area of the annular groove 8 exposed to the tobacco in the combustion chamber, the presence of the bleed passage 10 does not materially affect the draft of the combustion.

With my improved pipe it is not necessary that the tobacco be dry, because the adequacy of the air supply makes it possible to use tobacco that is unusually moist. Nor is the smoker obliged to relight the pipe at frequent intervals, since it will burn freely and evenly until all of the tobacco is consumed. Furthermore, the absence of the undesirable distillates hereinbefore mentioned, makes it unnecessary frequently to clean the pipe and prevents it from becoming "rank" and objectionable to others than the smoker.

It is to be understood that numerous alterations and changes may be made in the con-

struction of the pipe without departing from the scope of the invention as defined by the appended claims.

Having described my invention what I claim as new and desire to secure by Letters Patent, is:—

1. A tobacco pipe comprising a stem having a bore and a bowl portion having a combustion chamber, the wall of said combustion chamber being undercut on the side thereof adjacent said stem to form a chamber out of the line of pressure applied to the tobacco in said combustion chamber in filling the pipe, said combustion chamber having an annular groove above the bottom thereof and merging into said undercut chamber, said bowl portion having an air passage communicating at its outer end with the atmosphere, the inner ends of said air passage and

said bore communicating with said undercut 20 chamber substantially in the zone of said annular groove.

2. A tobacco pipe comprising a stem having a bore and a bowl portion having a combustion chamber of which the inner end is 25 enlarged at one side thereof and having a circumferential groove in its wall between its inner and outer ends and merging into said enlarged portion, said bowl also having an air passage of which the inner and outer 30 ends communicate, respectively, with said enlarged portion adjacent said groove and with the atmosphere, the inner end of said bore terminating in the enlarged portion of 35 said chamber adjacent said groove.

In testimony whereof I have hereunto set my hand.

GEORGE H. WILSON.
